H. F. MacGRATH

DISINFECTING ATTACHMENT FOR MONEY DRAWERS

Filed Sept. 27, 1923

UNITED STATES PATENT OFFICE.

HAROLD FAULDER MACGRATH, OF SYRACUSE, NEW YORK.

DISINFECTING ATTACHMENT FOR MONEY DRAWERS.

Application filed September 27, 1923. Serial No. 665,164.

To all whom it may concern:

Be it known that I, HAROLD FAULDER MACGRATH, a citizen of the United States of America, of Syracuse, in the county of Onondaga, in the State of New York, have invented new and useful Improvements in Disinfecting Attachments for Money Drawers, of which the following, taken in connection with the accompanying drawings, is a full, clear, and exact description.

This invention relates to a disinfecting apparatus for cash registers and analogous devices having money drawers for receiving paper and other currency.

It is well known that bills and other currency which is circulated extensively frequently become contaminated with disease-carrying germs to such an extent as to endanger the health of the users, and the main object of my present invention is to provide simple and efficient means for automatically disinfecting this currency as it is placed in the drawers or similar containers without special attention on the part of the operator.

In other words, I have sought to provide the cash register or other depository for the currency with a container for the disinfectant having distributing pipes and nozzles normally overlying the many pockets of the closed drawer or drawers and to equip the distributing system with suitable means actuated preferably by the opening and closing movement of the drawer for withdrawing the disinfectant from the container and discharging it over and upon the money in the drawer after the latter is closed.

Other objects and uses relating to specific parts of the device will be brought out in the following description.

In the drawings,

Figure 1 is a side elevation, partly in section, of a cash register and my improved disinfecting apparatus operatively mounted thereon, the drawer being shown in its partly open position.

Figure 2 is a horizontal sectional view taken on line 2—2, Figure 1.

Figure 3 is an enlarged detail sectional view taken in the plane of line 3—3, Figure 2.

Figure 4 is an enlarged sectional view through the closed end of one of the distributing pipes taken on line 4—4, Figure 2.

The money disinfecting device may be as-

sociated with any suitable case, as a cash register —A— having a money drawer —a— divided into a series of compartments —a'— for receiving currency of various denominations either bills or coins.

As illustrated, a reservoir or container —1— for the fluid disinfectant is supported upon a bracket —2— on the lower rear side of the case —A— with its lower end near the bottom of the chamber in which the money drawer —a— is movable and provided with an outlet nipple —3— extending through an opening —4— in the rear wall of the case —A— and operatively connected to one end of a horizontal piston pump —5—, the upper end of said container being provided with an inlet —6— through which the container may be filled with any desired disinfectant, capable of being withdrawn from the container and forced upon the money in the drawer —A— by the operation of the pump in a manner presently described, said disinfectant being preferably made in the form of a liquid adapted to be sprayed upon the currency in the several pockets —a'—.

The pump comprises a cylinder —7— and a piston —8— reciprocally movable therein preferably in the direction of movement of the drawer —a—.

The cylinder —7— is secured by screws —9— to the bottom of the casing —A— and is provided in its rear end with an axially extending inlet —10— and an upwardly extending outlet nipple or gland —11—, the inlet —10— being connected to the outlet nipple —3— of the reservoir —1— while the outlet nipple or gland —11— is connected to one end of a distributing pipe —12— having a plurality of, in this instance, two, branch distributing pipes —13— extending across the upper open sides of the several pockets —7'— of the money drawer —a— and having their free ends closed by suitable caps —14—, the intermediate portions of said branch pipes being provided in their undersides with relatively small openings —15— directly over the several pockets —a'— and constituting nozzles for spraying the disinfectant on to the currency in said pockets, particularly when the drawer is closed. (See Figure 4.)

The outlet nipple —3— of the reservoir —1— is provided with a check valve —17— adapted to be opened by the pressure of the

liquid in the reservoir —1— to admit said liquid to the piston chamber of the cylinder —7—, particularly when the piston —8— is withdrawn from the passage —10—.

5 The nipple or gland —11— is also provided with a check valve —18— adapted to open to allow the disinfecting liquid to flow from the cylinder —7— into the distributing pipes —12— and —13— and thence through the passages —15— on to the currency in the pockets —a'— of the drawer —a— as the piston is forced inwardly toward the passage —10—.

10 A coil spring —19— is interposed between the inner end of the piston and opposite end of the cylinder for normally forcing the piston away from the passage —10—, said piston being provided with a push rod —20— extending outwardly through a gland in the end of the cylinder opposite the passage —10— and into the path of movement of the rear end of the drawer —a— so that when the latter is closed, it will engage the push rod —20— and thereby force 15 the piston rearwardly against the action of the spring —19— where it may be held by the locking of the drawer in its closed position through the medium of any suitable catch not necessary to herein illustrate or 20 describe.

Operation.

Assuming that the reservoir —1— is filled with a fluid disinfectant and that the 25 drawer is in its closed position, thereby forcing the plunger —20— and its piston —8— inwardly toward the rear end of the cylinder and incidentally closing the check valve —17—, then in the event that the 30 drawer is pulled out to deposit currency in one or more of the pockets —a'— of the drawer —a— will allow the plunger —20— and piston —5— to be forced in the same direction by the action of the spring —19—

and will also allow the valve —17— to open 45 and permit the flow of the disinfecting fluid from the reservoir —1— into the cylinder —7—.

Now, if the drawer with the money therein is returned to its closed position, it will 50 force the plunger —20— and piston —5— inwardly against the action of the spring —19— thereby automatically closing the valve —17— and opening the valve —18— to permit the disinfecting fluid to pass 55 through the distributing pipes —12— and —13— and thence through the spray nozzles —15— directly on to the surface of the money in the several pockets —a'— for the 60 purpose of destroying any disease germs which may adhere to the currency, all of which renders the handling of the currency more hygienic and therefore, less dangerous to the health of the users.

I claim:

The combination with a case having a money drawer slidable therein, of a piston pump mounted in the case at the rear of the money drawer and provided with a piston rod projecting into the path of movement of said money drawer, a reservoir connected to the pump for supplying a disinfecting liquid thereto, a check valve controlling communication between the pump and reservoir; a discharge pipe leading 75 from the pump across the open top of the money drawer when the latter is closed, said piston rod and piston being actuated by the closing of the money drawer to force the disinfectant from the pump through said pipe, 80 and a spring for retracting the piston and piston rod and also for assisting in opening the drawer when the latter is released from its closed position.

In witness whereof I have hereunto set 85 my hand this 18th day of September 1923.

HAROLD FAULDER MACGRATH.
